UNITED STATES PATENT OFFICE.

SIGMUND BERGMANN, OF NEW YORK, N. Y.

KEY FOR ELECTRIC CUT-OUTS.

SPECIFICATION forming part of Letters Patent No. 445,364, dated January 27, 1891.

Application filed May 5, 1890. Serial No. 350,695. (No model.)

To all whom it may concern:

Be it known that I, SIGMUND BERGMANN, of New York, county and State of New York, have invented a certain new and useful Improvement in Attaching Devices for Keys for Electrical Cut-Outs, of which the following is a specification.

This invention relates more particularly to cut-outs adapted to be removably secured in the arm or bracket of a fixture; and it consists in means, substantially as hereinafter described, for removably attaching a key or finger-piece to the cut-out shaft. In cut-outs of this character it is desirable that the design of the finger-piece should have a relation to the design of the fixture, and the finger-pieces are therefore manufactured as a part of the fixture independent of the cut-out.

The object of my invention is to provide a cut-out to the shaft of which any key or finger-piece may be attached.

I will describe a cut-out embodying my improvement, and then point out the novel features in the claims.

In the accompanying drawings, Figure 1 is a central longitudinal section of a device embodying my improvement. Fig. 2 is a side elevation thereof. Fig. 3 is a front elevation. Fig. 4 is a section through the line $x-x$ of Fig. 3, and Fig. 5 shows a socket attachment for a key.

Similar letters of reference designate corresponding parts in all the figures of the drawings.

Referring by letter to the drawings, A designates a cut-out removably secured in a portion of a fixture B. A detailed description of the cut-out here shown is not deemed necessary, as it is fully described in a pending application, Serial No. 340,700, and I do not limit my present invention to any one form of cut-out. The cut-out may be described generally, however, as having a frame consisting of the metal portion a and the portion a' , of insulating material, forming bearings for the rotary shaft C, upon which is mounted a cut-out wheel a^2 to form connections with contact-plates a^3 . The rotary shaft C has a reduced portion c at its outer end, and in the main portion it has opposite longitudinal grooves or channels c' , extending a portion of

the length of the shaft and joined at the near end by a transverse perforation or hole c^2 through the shaft. The channels c' provide seats for spring-arms D D. The spring-arms are here shown as formed from one piece of metal, preferably spring-steel, having the transverse portion d passing through the hole c^2 in the shaft. Each spring-arm D has at its free end a lock portion or lug d' , extending outward at substantially right angles to the main portion of the arm, and the front surface of each lug d' is slightly inclined, as shown.

E designates an attaching-piece constructed to engage with the shaft C and the spring-arms and to have a key or finger-piece E' secured to it. The attaching-piece is here shown as tubular and having a portion of its interior enlarged at e to pass over a section of the main portion of the shaft C, the reduced portion c of the shaft passing into the smaller interior e' . Opposite perforations e^2 are provided through the attaching-piece, and the inner end surface is beveled, as at e^3 .

To place the attaching-piece in position, it is pushed onto the shaft C. The bevel e^3 , striking against the incline of the lugs d' , forces the spring-arms toward each other until the lugs are in line with the perforations e^2 , into which they spring, locking the parts together.

The engaging-piece may be removed from the shaft C by compressing the spring-arms by means of a suitable tool.

The attaching-piece E has a reduced threaded portion e^4 , to which a key E' may be secured by providing said key with an internally-threaded socket, as shown. If desired, the reduced portion may also be soldered in the socket, and it is obvious that the key may be attached in other ways than that shown without departing from the spirit of my invention.

Having described my invention, what I claim is—

1. In a cut-out, the combination, with the rotary shaft having the channels and reduced portion at its end, and spring-arms, of the tubular attaching-piece having the enlarged inner portion to engage over a section of the main portion of the shaft and the smaller in-

ner portion to engage over the outer portion of the shaft, and perforations to engage lugs on the spring-arms, substantially as specified.

2. In a cut-out, the combination, with the
5. rotary shaft having the channels and the trans-
verse hole, of the spring-arms seated in said
channels and having an integral transverse
portion extended through the transverse hole

in the shaft, and the key or finger-piece con-
structed to removably engage with said shaft 10
and spring-arms, substantially as specified.

SIGMUND BERGMANN.
